DISPLAY STAND FOR HOsing OR THE LIKE

Donald M. Hanson, Mount Prospect, Ill., assignor to
O.E.M. Products Co., Des Plaines, Ill.

Filed July 24, 1974, Ser. No. 491,536

Term of patent 14 years

Int. Cl. D20—02

U.S. Cl. D6—85

FIG. 1

FIG. 2

FIG. 3

FIG. 4

FIG. 5

FIG. 6

FIG. 7

FIG. 1 is a perspective view showing my new ornamental design for a display stand for hosing or the like;

FIG. 2 is a top plan view of the display stand;

FIG. 3 is a front elevational view of the display stand;

FIG. 4 is a bottom plan view of the display stand;

FIG. 5 is an elevational view of the right side of the display stand;

FIG. 6 is an elevational view of the left side of the display stand; and

FIG. 7 is an elevational view of the rear of the display stand.

I claim:

The ornamental design for a display stand for hosing or the like, as shown.
